Atty's:

UNITED STATES PATENT OFFICE

JOSEPH KAHN, OF CHICAGO, ILLINOIS

LOOSE-LEAF BINDER

Application filed January 14, 1929. Serial No. 332,428.

This invention is an improvement in loose leaf binders of the class to which my Patent No. 1,647,635 relates. The main objects of this invention are to provide an improved lock for securing loose leaves in bound condition, and which conveniently may be manipulated by a single hand; to provide means for moving a locking member of the loose leaf binder into and out of locking position by a camming action; to provide a pivotal connection between the binder cover and leaf holding elements for facilitating convenient removal and replacement of loose leaves without straining the materials comprising the cover; to provide an improved attachment for securing a leaf holding device in a binder cover without requiring a rigid reinforcing rib, rivets or other similar rigid means extending through the cover; to provide a device of the class described in which the leaf holding mechanism is completely concealed from sight and entirely covered by soft material to avoid injuring polished surfaces; to provide an improved construction whereby all operating parts are retained out of forced engagement with the binder cover; and to provide a device of the class described in which parts of inexpensive construction may be employed without cheapening its appearance or impairing its strength and durability.

In the accompanying drawings, I have shown embodiments of my invention, in which:

Figure 1 is a fragmentary plan of an open binder showing a locking bar in locked position.

Fig. 2 is a view similar to that shown in Fig. 1, illustrating the locking bar in unlocked position.

Fig. 3 is a section taken on the line 3—3 of Fig. 1.

Fig. 4 is a fragmentary section taken on the line 4—4 of Fig. 1.

Fig. 5 is a fragmentary perspective showing elements in position for assembling.

Fig. 6 is a fragmentary detail of one form of a bearing member.

Fig. 7 is a fragmentary perspective of a modified form of my invention.

In general my invention comprises an in-

tegral binder cover having spaced bearing members or rods attached thereto. A substantially rigid strip is pivotally mounted on each rod. One strip is provided with extensible posts for insertion through apertures in loose leaves and the other strip is provided with apertures for receiving the ends of the posts. A locking bar is slidably mounted on the apertured strip and improved means is provided for camming the locking bar laterally into and out of locked engagement with the top of the posts.

In the form shown in Figs. 1 to 5 inclusive, the binder cover 1 comprising flexible material such as leather or rubberized fabric is provided at its middle portion on its inner side, with a flexible liner 2. Any suitable flexible material such as rubberized fabric may be used and its longitudinal edge portions may be looped or beaded as shown at 3 and 4 in the drawings. The edges are tucked underneath and secured by stitches 5, between the liner and the cover, and the liner is also secured at its ends by stitches 6 which extend through the cover 1. Cylindrical bearing members comprising rods 7 and 8 are inserted in the beads 3 and 4 respectively and terminate intermediate the ends of the beads. The beads are slit adjacent the ends of the bearing members as shown at 9 in Fig. 5. Rigid strips 10 and 11 comprising hinged elements 12 are pivotally mounted on the bearing members 7 and 8 respectively by pintles 13, which extend through the tubular portions 14 of the hinge elements, and into the end portions of the members 7 and 8.

The tubular portions 14 of the hinged elements are smaller in diameter than the rods 7 and 8, and thus they are held away from the flattened portions 15 of the beads 3 and 4 and from the cover 1.

Extensible binder posts 16 are provided comprising sockets 15 secured to the strip 10, the posts 16 being threaded in the sockets 15, as shown in Fig. 3.

A cylindrical projection 17 is provided on the upper end of each post 16 and terminates with a head 18. The other strip 11 is provided with spaced apertures 19 for receiving the 106

projections and heads 17 and 18 respectively. An extensible post comprising a sleeve 20 and a threaded stud 21, is located midway between the posts 16. The stud 21 is rigidly secured to the strip 10 and the sleeve 20 is provided with a slot by means of which it may be turned upwardly or downwardly as required, for accommodating various thicknesses of leaves.

A locking bar 22 is slidably mounted on the strip 11 by rivets 23, which extend through lateral slots 24 in the locking bar. The locking bar has irregular apertures 25 therein, which comprise a constricted portion for receiving the cylindrical projection 17 of the posts 16 for securing the strip 11 on the top of the posts in superimposed relation to the strip 10. The strip 11 is provided with a diagonally extending slot 26 which registers with a longitudinally extending slot 27 in the locking bar and a rivet 28 is slidably mounted in these slots. When the rivet 28 is moved from its lower position shown in Fig. 1, to its uppermost position shown in Fig. 2, the locking bar 22 is moved laterally to the right, as viewed in Fig. 2 to unlocked position by a wedging action. When the rivet is moved downwardly from the position shown in Fig. 2, the locking bar 22 is moved to locked position.

The rods 7 and 8 are shown in detail in Fig. 6 as having apertured extremities 29 and 30 but the tubular members 7' and 8' shown in Fig. 7, are sometimes used.

The leaf holding device may be mounted on a rigid binder cover of the form shown in Fig. 7 if desired, by placing the bearing members 7 and 8 in position and gluing or cementing thereover a liner member 31. In this form of my invention the liner is slit at the ends of the tubular members 7 and 8 for permitting the pintles 13 to be inserted into the ends of the tubes. With this form of my invention it is particularly advantageous to employ hinge elements having tubular portions of smaller diameter than the bearing members in order that the pivotal portions of the device may be held free from the cover thus avoiding wear thereof.

The pivotal connection between the binder cover and the leaf holding strips permits the device to be conveniently opened and closed for facilitating the removal and replacement of loose leaves without straining the cover.

Considerable force may be applied on the locking bar 22 by the wedging action created when the rivet 28 is moved, and this locking action may be easily accomplished with a single hand. The extensible binder posts allow various thicknesses of leaves to be bound in the cover, and assure a firmly compact arrangement.

It will be understood that the back portion 32 of the cover will be bulged outwardly when a small stack of leaves is employed, and that it will be stretched substantially straight

when a stack of maximum size is mounted in the cover. This adaptability of the portion 32 of the cover to the size of the stack therein is made possible by the absence of rigid elements such as transverse ribs heretofore used in the construction of loose leaf binders. All of the metallic portions of the binder are concealed from sight, and are entirely covered by the soft material of the cover so as to avoid all possibilities of scratching desk tops or other polished surfaces.

Although but two specific embodiments of my invention have been herein shown and described, it will be understood that details of the construction shown may be altered or omitted without departing from the spirit of this invention as defined by the following claims.

I claim:

1. In combination with a loose leaf binder cover, strips secured thereto, one of said strips having apertures and a slot therein, posts on the other strip for insertion through said apertures and through apertures in loose leaves, a locking bar slidably mounted on the apertured strip engageable with said posts and having a slot therein extending at an angle to the slot of said apertured strip, and means extending through said slots coacting between the latter strip and the locking bar thereon for wedging the locking bar into and out of locking position.

2. In combination with a loose leaf binder cover, a strip secured to said cover, binder posts on said strip for insertion through apertures in loose leaves, a second strip secured to said cover having a diagonal slot and spaced apertures for receiving said binder posts therein, locking means comprising a bar slidably mounted on said second strip having a longitudinally slot therein in registration with said diagonal slot, and means extending through said registering slots for wedgingly moving said locking bar laterally of the second-mentioned strip into and out of engagement with said posts.

3. In combination with a loose leaf cover, a rigid strip pivotally mounted on said cover, binder posts on said strip, a second strip pivotally mounted on said cover having a diagonally extending slot and apertures for receiving said binder posts therein, locking means mounted on said second strip having a longitudinally extending slot therein in registration with said diagonal slot, and means extending through said registered slots for moving said locking bar laterally thereof into and out of locking engagement with said binding posts.

4. In combination with a binder cover, spaced bearing members secured thereto, strips pivotally attached to said bearing members, binding posts on one of said strips, locking means slidably mounted on the other strip engageable with said binding posts, and

means coacting with the latter strip and the locking means thereon for wedgingly moving said locking means laterally into and out of locking engagement with said posts.

5. In combination with a binder cover, a lining secured thereto comprising spaced beads, a bearing member in each of said beads having apertured extremities, strips comprising hinge elements, pintles mounted in each hinge element, said pintles extending into the apertured extremities of said bearing members, posts on one of said strips, and locking means on the other strip engageable with said posts for securing said strips on opposite sides of a stack of loose leaves.

15. 6. In combination with a binder cover, a flexible member secured to the intermediate portion of said binder cover comprising spaced beads, bearing members comprising rods having hollow end portions mounted in said beads, hinge elements comprising a cylindrical portion, means on said cylindrical portion pivotally mounted in said bearing members, said cylindrical portion being of smaller diameter than said bearing members 20 for preventing wearing of said cover, and clamping strips carried by said hinge elements for securing loose leaves in said binder cover.

30. 7. In combination with a loose leaf binder cover, a pair of strips pivotally mounted thereon, one of said strips being provided with spaced apertures and intermediate slot, posts on the other strip for insertion through apertures in loose leaves and through the apertures 35 in said apertured strip, locking means slidably mounted on the apertured strip having a slot therein extending at an angle to the slot in said apertured strip, and means in said slots for moving said locking means into and out of engagement with said posts.

Signed at Chicago this 12th day of January 1929.

JOSEPH KAHN.
